UNITED STATES PATENT OFFICE.

WALTER J. GADSBY, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,802, dated March 14, 1882.
Application filed February 6, 1882. Term of patent 3½ years.

To all whom it may concern:

Be it known that I, WALTER J. GADSBY, of Boston, in the county of Suffolk and State of Massachusetts, have invented a new and original Design for a Carpet, of which the following is a specification.

The nature of my design is fully shown in the accompanying photographic illustration.

The design is composed chiefly of thick masses of foliage having blossoms and relieved by light centers, partially covered by the foliage and blossoms.

The design also includes a rustic building and trees in foliage near the building, as shown.

I claim—

The design for a carpet, substantially as shown and described.

In testimony whereof I have signed my name to this specification, in the presence of two subscribing witnesses, this 2d day of February, 1882.

WALTER J. GADSBY.
